METHOD OF MANUFACTURING METAL DIALS.

Application filed August 31, 1925, Serial No. 53,762, and in Switzerland September 11, 1924.

Our invention relates to a method of manufacturing metal dials similar to those provided with a series of characters marking the hours which project beyond the surface 5 of the dial and are made of two materials both, e. g. either of both metal and enamel, or of metal and any substance luminous in the dark.

Hitherto the embossed dial characters of 10 the metal and the luminous substance type were generally made in such a manner that a channel-shaped figure (see Fig. 4 and Fig. 5 which is a section of the former along the line V—V) was at first fashioned separately and secured to the dial in proper position after having undergone the previous 15 stamping operations.

Our device is by far more simple: Its distinctive feature is that one stamping operation will be sufficient to fashion, for each 20 character marking the hours, a channel which, projecting beyond and making one body with the dial, has the outer outline of said character and is afterward filled with 25 a substance of another kind, such as enamel.

The accompanying drawing illustrates one manner in which the invention is employed. Fig. 1 is a front view of a dial; Fig. 2 is a section through it along the line II—II of 30 Fig. 1; Fig. 3 is a similar section but on a larger scale; Fig. 4 is an enlarged plan view of a pre-formed index figure of the type hitherto used in making watch dials; Fig. 35 5, is a section taken through the index figure shown in Fig. 4.

a represents the bed-plate of the dial, whilst *b* are the figures marking the hours from 1 to 12 and *c* the graduations showing the minutes; each figure and each graduation is formed from a channel-shaped or cup-shaped projection filled out with a material *e* which may be, e. g. either enamel or any substance luminous in the dark. All outlines *d* are made in one stamping operation carried out on the plate *a*; this single 45 operation provides flanged outlines or channels *d* which will be arranged directly on the plate *a* in the predetermined position. The stamping once completed, the frames are filled with either enamel or any substance 50 luminous in the dark.

We claim:

1. The method of manufacturing metal dials which consists in stamping a dial to provide said dial with indices, each of said 55 indices consisting of a channeled outline projecting from the surface of the dial, and filling the channels with a substance differing from the metal of the dial.

2. The method of manufacturing metal 60 dials which consists in stamping a dial to provide said dial with indices, each of said 65 indices consisting of a channeled outline projecting from the surface of the dial, and filling the channels with an enamel.

In testimony whereof we affix our signatures.
